CHARLES GITZENDANNER, OF NEW YORK, N. Y., ASSIGNOR TO KAST INSETTING & GATHERING MACHINE COMPANY, OF NEW YORK, N. Y., A CORPORATION OF DELAWARE.

SIGNATURE-HANDLING MECHANISM.

1,142,417.

Specification of Letters Patent.

Patented June 8, 1915.

Original application filed September 25, 1911, Serial No. 651,048. Divided and this application filed April 9, 1914. Serial No. 830,641.

To all whom it may concern:

Be it known that I, CHARLES GITZENDANNER, of New York city, in the county and State of New York, have invented a new and useful Improvement in Signature-Handling Mechanism, which invention is fully set forth in the following specification.

The present invention is an improvement in signature-handling mechanism, and this application is a division of application Serial No. 651,048, filed September 25, 1911, book or pamphlet making machines.

The objects of the present invention are to progress signatures along a support or saddle with the minimum of friction, to accurately align the various signatures of each group that constitutes a book or pamphlet and to maintain said signatures in accurate alinement as they are progressed along said support or saddle to stitching or other mechanism.

The first object is attained by supporting the signatures by movable means projecting through the apex of the stationary saddle, said movable means supporting the signatures at a point above the stationary saddle whereby the latter acts simply as a guide to hold the signatures open. The other objects are attained by providing above the saddle and longitudinally thereof a signature-supporting member on which the signatures are deposited either manually or mechanically and from which they are removed, onto the movable means above referred to, by signature-engaging devices that pass along the saddle with said movable means.

It is pointed out that heretofore the friction between the innermost signature of each group and the saddle was very great, this being due to the fact that the signatures were entirely supported by the saddle. This friction caused the innermost signature to be forced against the signature-engaging means, usually a pin carried by the conveyer chain, that progressed the signatures along the saddle, thus bending or crumpling the edge of said signature and causing the same to get out of alinement with the other signatures. This objection has been obviated by the present invention.

It is further pointed out that if the signatures were deposited directly on the saddle or on the movable means referred to,

difficulty would be experienced in causing them to exactly register with the signature-engaging means. By depositing them, however, on a supporting member in position to be engaged by the signature-engaging means and from which member they are readily removed onto the movable means projecting through the saddle, the signatures in each group are maintained in register with the signature-engaging means and in exact alinement with each other.

The invention will be better understood by reference to the accompanying drawings, illustrating one expression of the inventive idea, and wherein—

Figure 1 is a fragmentary elevation, 70 showing the saddle, parts of the conveying chain, the signature-engaging pins and two supporting members on which the signatures are first deposited; Fig. 2 is a transverse section through the saddle and the movable 75 means on which the signatures rest; Fig. 3 is a side elevation corresponding to Fig. 2; and Fig. 4 is a perspective view showing a signature resting on a supporting member in position to be contacted by a signature- 80 engaging finger.

Referring to the drawings, wherein like reference numerals indicate like parts, 190 indicates a substantially horizontal saddle mounted upon supports 191 upon the machine frame. While, generally, this saddle is used in association with means for mechanically opening signatures, it is to be understood that the signatures may be manually deposited thereon; and, whether 90 the signatures are manually or mechanically deposited they are supported on the saddle with the back edge upward. When the registering device or supporting member, hereinafter described, is used, the signatures 95 will first fall or be deposited upon it. It will be seen that, when a signature falls, if one or more signatures are beneath it upon the saddle, they will be inset with it. A sprocket chain 193 is associated with the 100 saddle, and signature-engaging means, here shown as pins 192, are carried by said chain and engage the edges of the signatures. These pins 192 project through a slot at the apex of the saddle. Means are also provided, by one feature of the invention, for minimizing the friction between the signatures and the saddle as the signatures are

progressed along the saddle and thus preventing bending or crumpling of the edges of the innermost signature by the pin 192, whereby it will be out of register with the 5 other signatures when inset therewith. To this end, I have, in the embodied form, mounted on the conveyer chain a series of movable elements 189 that project through and above the saddle and in effect constitute 10 a movable or separate crown or apex for the saddle. Each element or section is suitably attached to a link of the sprocket chain. The movable elements therefore travel with the chain and, being higher than the remainder of the saddle, support the signatures so that there is practically no friction 15 between the signatures and the stationary parts 190 of the saddle, which parts thus act simply as a guide to hold the signatures open. By thus supporting the signatures as they are progressed along the saddle and eliminating friction, the signatures will be kept in alinement and in register with pins 192, if they have been properly alined and 20 registered in the first place. Means are therefore provided for insuring the registry of the successively dropped signatures whereby the signatures in any one group will be in alinement with each other upon 25 the movable elements 189. In the embodied form a plurality of supporting members, here shown as bars 218, are employed, said bars being arranged above the saddle so that the signatures may be removed therefrom into engagement with the saddle. The 30 signatures are either manually or mechanically deposited on said bars.

In Fig. 1, 110 and 111 indicate two sets of any suitable signature-opening mechanisms that may be employed. Each bar is supported by an arm 219 from a rod 217, and is arranged horizontally and longitudinally of the direction of travel of the signatures. Preferably each bar is substantially 45 in line above the apex of the saddle. The free end of the bar, that is, the other end from that to which the supporting arm 219 is attached, extends in the direction of travel of the fingers 192 along the saddle 190, so 50 that the signature may be slid off the bar.

In the operation of the form of device illustrated, the signatures, whether deposited manually or mechanically, are deposited in open position on the supporting members 55 or bars 218. When the pin 192 arrives, if we assume that it has one signature, that signature will be registered against said pin which engages the edge thereof. This pin 192 will contact with the edge of the opened 60 signature suspended upon the bar 218. This latter signature will then be readily slid along the bar 218 by the pin 192 and, by reason of the inclination of the bar, will pass below the next succeeding bar 218 and 65 into engagement with the saddle 190. It

will finally drop off the bar 218 completely and having been in registry with the pin 192 during the entire time, it will therefore be in registry with the preceding signature which was brought up by the pin 192, as described. It will thus be seen that all the successive signatures inset, and picked up by any particular pin 192, will be accurately alined and registered, and, further, that in view of the construction described for progressing the groups of signatures along the saddle without friction, the signatures will be maintained in alinement and register. 75

While, for the purpose of illustration, one expression of the inventive idea has been shown and described with great particularity, it is to be understood that the invention is not limited to the embodiment shown but that the inventive idea may receive various mechanical expressions within the limits of 80 the claims annexed hereto. 85

I claim:

1. In combination, a support or saddle along which groups of signatures are conveyed, a conveyer movable along said saddle, 90 supporting elements carried by said conveyer and projecting above said saddle, and signature-engaging means carried by said conveyer.

2. In combination, a support or saddle along which groups of signatures are conveyed, a conveyer movable along said saddle, a plurality of projections carried by said conveyer and projecting above said saddle, and signature-engaging means carried by 100 said conveyer.

3. In combination, a support along which groups of signatures are conveyed, a conveyer movable along said support, supporting means carried by said conveyer and engaging the signatures above said support, and signature-engaging means carried by 105 said conveyer.

4. In combination, a support along which groups of signatures are conveyed, a conveyer movable along said support, supporting means movable with said conveyer and engaging the signatures above said support, and signature-engaging means carried by 110 said conveyer.

5. In combination, a support on which signatures are held in open position, a member arranged above and longitudinally of said support on which signatures are held in open position, and a traveling device 120 which engages the open signatures on said member and removes them endwise therefrom onto said support.

6. In combination, a member on which signatures are held in open position, and a support on which the signatures are held open arranged below said member, said support including stationary and movable parts, and a traveling signature-engaging device 125 that removes the signatures endwise from 130

said member into engagement with said support.

7. In combination, a member on which signatures are held in open position, and a support on which the signatures are held open arranged below said member, said support including stationary parts and a movable part projecting above said stationary parts, and a traveling signature-engaging device that removes the signatures endwise from said member into engagement with said support.

8. In combination, a member on which signatures are held in open position, and a support on which the signatures are held open arranged below said member, said support including stationary and movable parts, and a signature-engaging device traveling with said movable part and acting to remove the signatures endwise from said member into engagement with said support.

9. In combination, a member on which signatures are held in open position, and a support on which the signatures are held open arranged below said member, said support including stationary parts and a movable part arranged between said stationary parts and projecting above the same, and a signature-engaging device traveling with said movable part and acting to remove the signatures endwise from said member into engagement with said support.

10. In combination, a support on which signatures are held in open position, a plurality of members arranged above and longitudinally of said support on which a plurality of signatures are held in open position, and a plurality of traveling devices which engage the open signatures on said members and remove them endwise therefrom onto said support whereby one signature is inset within another.

11. In combination, a plurality of members on which signatures are held in open position, and a support arranged below said members on which the signatures are held open, said support including stationary and movable parts, and a plurality of traveling signature-engaging devices that remove the signatures endwise from said members into engagement with said support, whereby one signature is inset within another.

12. In combination, a plurality of members on which signatures are held in open position, and a support on which the signatures are held open arranged below and longitudinally of said members, said support including stationary parts and a movable part projecting above said stationary parts, and a plurality of traveling signature-engaging devices that remove the signatures endwise from said members into engagement with said support whereby one signature is inset within another.

13. In combination, a plurality of mem-

bers on which signatures are held in open position, and a support on which the signatures are held open arranged below and longitudinally of said members, said support including a plurality of signature-engaging devices acting to remove the signatures endwise from said members into engagement with said support whereby one signature is inset within another.

14. In combination, a plurality of members on which signatures are held in open position, and a support on which the signatures are held open arranged below and longitudinally of said members, said support including stationary parts and a movable part arranged between said stationary parts and projecting above the same, and a plurality of signature-engaging devices traveling with said movable part and acting to remove the signature endwise from said members into engagement with said support whereby one signature is inset within another.

15. A signature gatherer or insetting machine for assembling folded signatures, including in combination a signature conveying saddle having slanting sides upon which an opened signature may rest with its back edge upward, means within said saddle and projecting upwardly between said sides for engaging the signatures and sliding them along said saddle, and supporting elements for said signatures projecting above said sides and traveling with said signature sliding means.

16. A signature gatherer or insetting machine for assembling folded signatures, including in combination a saddle having inclined separated sides, a sprocket chain traveling within said sides, a finger associated with said sprocket chain to slide signatures along said saddle, and supporting elements for said signatures projecting above said sides, said elements consisting of a plurality of separate sections traveling with said chain.

17. A signature gatherer or insetting machine for assembling folded signatures, including in combination a saddle having inclined separated sides, a sprocket chain traveling within said sides, a finger extending upwardly from said sprocket chain to slide signatures along said saddle, and an apex for said saddle consisting of a plurality of separate sections fixed to and traveling with said chain.

18. In combination, a support or saddle along which groups of signatures are conveyed, a supporting member arranged above said saddle on which supporting member signatures are deposited, a conveyer movable along said saddle, supporting means carried by said conveyer and projecting above said saddle, and signature-engaging means carried by said conveyer

- and removing the signatures from said supporting member onto said supporting means carried by the conveyer.
19. In combination, a support or saddle along which groups of signatures are conveyed, a supporting member arranged above said saddle on which supporting member signatures are deposited, a conveyer movable along said saddle, a plurality of 10 projections carried by said conveyer and projecting above said saddle, and signature-engaging means carried by said conveyer and removing the signatures from said supporting member onto said plurality of elements carried by the conveyer.
20. In combination, a support along which groups of signatures are conveyed, a supporting member arranged above said support, on which supporting member signatures are deposited, a conveyer movable along said support, supporting means carried by said conveyer and engaging the signatures above said support, and signature-engaging means carried by said conveyer and removing the signatures from said supporting member onto said supporting means carried by the conveyer.
21. In combination, a support along which groups of signatures are conveyed, a supporting member arranged above said support, on which supporting member signatures are deposited, a conveyer movable along said support, supporting means movable with said conveyer and engaging the signatures above said support, and signature-engaging means carried by said conveyer and removing the signatures from said supporting member onto said supporting means movable with said conveyer.
22. In combination, a conveyer for groups of signatures, supporting elements for said groups carried by said conveyer and projecting upwardly, a member arranged above and longitudinally of said conveyer on which signatures are held in open position, and signature-engaging means associated with said elements and removing said signatures from said member onto said elements.
23. In combination, a linked conveyer for groups of signatures, supporting elements for said groups carried by said conveyer and projecting upwardly, a member arranged above and longitudinally of said conveyer on which signatures are held in open position, and signature-engaging means associated with said elements and removing said signatures from said member onto said elements.
24. In combination, a linked conveyer for groups of signatures, supporting elements for said groups carried by said conveyer and projecting upwardly, said elements being of inverted V-shape in cross-section and one being carried by each link, a member arranged above and longitudinally of said conveyer on which signatures are held in open position, and signature-engaging means associated with said elements and removing said signatures from said member onto said elements.

In testimony whereof I have signed this specification in the presence of two subscribing witnesses.

CHARLES GITZENDANNER.
